UNITED STATES PATENT OFFICE.

WILLIAM C. WATSON, OF PATERSON, AND JOSEPH N. MILEHAM, OF RUTHERFORD, NEW JERSEY.

CAR-COUPING.

SPECIFICATION forming part of Letters Patent No. 441,267, dated November 25, 1890.

Application filed August 15, 1890. Serial No. 362,072. (No model.)

To all whom it may concern:

Be it known that we, WILLIAM C. WATSON, of Paterson, in the county of Passaic and State of New Jersey, and JOSEPH N. MILEHAM, of Rutherford, in the county of Bergen, in said State, have invented a certain new and useful Improvement in Car-Couplings, of which the following is a specification.

Our invention relates to what are known as "rotary" or "knuckle" couplings.

The object of the improvement is twofold—viz., first, to afford greater flexibility, and thereby reduce the liability to breakage in turning curves, and, second, to provide in a simple and effective manner for the operation of such a coupling from the side, roof, or platform of the car, avoiding the necessity of a man having to go between the cars, which is always more or less a dangerous operation.

We will first describe our invention with reference to the accompanying drawings, and then point out its novel features in claims.

Figure 1 represents a horizontal section of a coupling embodying our improvement with a portion of a second coupling in operative position therewith, the section being taken on the line $x-x$ of Fig. 2. Fig. 2 represents a central vertical section of the same. Fig. 3 is a view in front elevation. Figs. 4 and 5 are plan views of portions of two couplings in different positions.

Similar letters of reference designate corresponding parts in all the figures.

A represents a buffer-head arranged on the under side of the car-body S and adapted to be moved lengthwise, but held against lateral displacement and guided in its longitudinal movement by guides a, secured to the car-body, and further retained in position by plates a' a'', here shown as bolted to the guides c. This buffer-head consists of a hollow shell, but is otherwise of ordinary construction, and is provided on its under side with a projection a³, which by its contact with the said plate a' limits the longitudinal movement of the buffer-head.

B designates a draw-head, having pivoted to its outer end a coupling-hook c of the kind commonly known as "rotary" or "knuckle" coupling-hook, consisting of an elbow pivoted at its bend, and one arm b⁷ of which consti-

tutes the engaging-hook, and the other arm b⁸ serves to engage with the locking device to keep the coupling in engagement. The draw-head B consists of a bar, here shown as 55 of skeleton construction, and is partly contained in the buffer-head A. Near its rear end it is connected by means of a pin b' to the draw bar or rod b, which passes through the rear of the buffer-head. The said pin b' 60 projects through longitudinal slots a⁴, formed in the top and bottom of the buffer-head, the said slots permitting a longitudinal movement of the draw-head B and bar or rod b relatively to the buffer-head. The said pin 65 b' is represented as removable from the bottom for taking out the draw-head B and as kept in place by means of the guide-plate a².

The draw bar or rod b passes through a lug b², formed upon a plate b³, secured to the bottom of the car. The buffer-spring b⁴ surrounds the said bar or rod between the rear end of the buffer-head and the lug b², the said lug serving as an abutment for said spring. This spring tends to press the buffer-head forward, so that in the normal condition of the parts the front of the buffer is 70 against a shoulder i on the draw-head.

The portion of the draw bar or rod b which projects rearward through a beyond the lug 75 b² is screw-threaded and receives a nut b⁶. Surrounding the said rearwardly-projecting portion is a coil-spring b⁵, one end of which abuts against the lug b², and the other end against the nut b⁶. This permits to the coupling-bar a longitudinal movement of the draw-head B relatively to the buffer-head when traction is applied to it.

The coupling-hook or knuckle B' is substantially like that of the knuckle-coupling 80 in common use, but may be here briefly described. It is pivoted to the draw-head B by means of a pin b⁹, and is provided with a hook portion b⁷ and an angularly-extending arm b⁸, the end of which arm is rounded, as 85 here shown at b¹⁰.

D is a rock-shaft arranged transversely under the car in bearings in hangers d, dependent from the car. This shaft carries a locking arm or stop d', which passes through a slot d² in the bottom of the shell of the buffer-head, as shown in Figs. 1 and 2, for the 90 95

purpose of acting against the inner face B'' of the arm b^8 in such manner as to lock the knuckle or coupling hook B' in operative position.

- 5 In Figs. 1, 4, and 5 we have shown sufficient portions of a second coupling to illustrate the operation of the invention, the buffer-head, the draw-head, and the knuckle of this second coupling being respectively designated by A^* , B^* , and B'^* . Fig. 1 shows the relative position of the parts of the two couplings when the two coupled cars to which they belong are on a straight track. Fig. 4 shows the relative position when the cars are on a curve in one direction, and Fig. 5 the relative positions on a curve in the other direction. When the cars are running free on a straight track, the only contact between the couplings is between the hooks b^7 of the knuckles B' B' ; 10 but in turning a curve the front of one or other of the buffer-heads, according to the direction of the curve, is brought into contact with the end of the other draw-head, as shown at j in Figs. 4 and 5, and that draw-head is held back with its shoulder i in contact with its own buffer-head, as shown at the bottom of Fig. 4 and top of Fig. 5, while the said draw-head pushes back the other buffer-head relatively to its draw-head to an 15 extent permitted by the slot a^4 in the shell of the buffer-head and by the spring b^4 , and the strain between the knuckles being then taken up by the said spring the liability to break the knuckles, which is one of the great 20 objections to the knuckle-coupling, as ordinarily applied, is obviated.
- It has been hereinbefore mentioned how the coupling-hook or knuckle B' is locked in its operative position by means of the stop d' . 25 To uncouple, the transverse shaft D is turned in a direction for the stop d' to move back clear of the arm b^8 . The hook B' is then free to rotate. To provide for turning the shaft for locking and unlocking the hook, it has 30 provided at its opposite ends levers d^3 , here shown as three-arm levers, by which it may conveniently be turned from the outside of the car. Fastened on said shaft on one side of the coupling is an arm d^4 , which forms in 35 effect a crank, and which engages a slotted yoke d^5 on one end of an upright pull-rod D' . Said pull-rod is fitted to slide in guides d^6 , attached to the front of the car or car-platform, and is provided at its upper end with a handle 40 d^7 . If preferred, therefore, to uncouple the car from the platform or roof, the pull-rod D' may be grasped at the handle d^7 and pulled

upwardly, rotating the crank d^4 and with it the transverse shaft D and stop d' .

This coupling constructed as described is 60 automatic or self-closing, as by the action of two cars coming together with one or both of the couplings in unlocked adjustment the pressure which would be brought against the inner face b'' of the arm b^8 of the coupling-hook, which is then presented crosswise of the car, would force the before-mentioned portion b^{10} against the rounded edge d^8 of the stop d' , pressing it backward and rocking the shaft D until the said arm should pass it. 70 The said stop would then, by the weight of the pull-rod D acting through the crank d^4 on the rock-shaft D , be caused to fall back to its normal position to lock the coupling. It is therefore never necessary for a man to go between the cars either to couple or to uncouple them, as this may conveniently be done either from the car roof (or platform) or from either side of the car. 75

We have shown a hole e and a cut-away 80 portion e' in the coupling-hook B' to provide for coupling a car which has our improved coupling attached thereto to another car which is only provided with an ordinary link-and-pin connecting device. 85

What we claim as our invention, and desire to secure by Letters Patent, is—

1. The combination of a hollow buffer-head, a draw-head separate from but fitted within the buffer-head, a rotary coupling-hook consisting of an elbow pivoted to said draw-head, and a locking device for said coupling-hook, substantially as herein described. 90

2. The combination of the hollow buffer-head A , having longitudinal slots a^4 , the draw-head B and draw-bar b and their connecting-pin b' working in said longitudinal slots, the rotary coupling-hook B' , pivoted to said draw-head, the springs b^4 b^5 , applied, respectively, to the buffer-head and draw-bar, and the abutment b^2 for said springs, all substantially as herein set forth. 95

3. In a car-coupling, the combination, with a draw-head, of a coupling-bar having a pivotal connection therewith, a rotary coupling-hook pivoted to said coupling-bar, a retaining-lock bearing against an arm of said hook, and a transverse shaft to which said lock is secured, substantially as specified. 100
